UNITED STATES PATENT OFFICE.

GEORGE E. MARLATT, OF PASADENA, CALIFORNIA.

SPACE-BAND-RELEASING MEANS FOR TYPOGRAPHICAL ASSEMBLING MACHINES.

Application filed November 13, 1926. Serial No. 148,303.

My invention relates to typographical machines of the kind in which circulating matrices are released by keyboard means from a storage magazine and assembled into a line representing words, the words being separated by expansible spacers (commonly designated spacebands) which are released from a storage box as required and subsequently separated from the line of matrices and returned to the box from which they were released. My objective is to provide an improved escapement for controlling the release of these spacebands from their storage box. The manner of attaining this objective is illustrated in the accompanying drawings, in which—

Fig. 1 is an elevation of a portion of the front of a typographical machine of the linotype class, showing my improvement applied thereto;

Fig. 2 is an elevation of the spaceband box separate from the machine;

Fig. 3 is a section on the line 3—3 of Fig. 2.

Figs. 4 and 5 represent a spaceband. Spaceband escapements as heretofore employed involve lifting or otherwise displacing the spacebands preliminary to their actual release, with power-driven cam means interposed between the releasing key and the escapement in order that the releasing key may have a light "touch". My present improvement contemplates an escapement sufficiently sensitive to permit of a direct connection between the releasing key and the escapement, thus eliminating such interruptions as are attributable to the improper functioning of the usual power driven devices; incidentally I provide an escapement more visible and accessible than those in common use.

Referring to the drawings: The spaceband wedge S^1 has the usual central recess S^2 in which the sleeve S^3 is fitted. At the lower end of the wedge this recess is of sufficient depth to permit a stopping and releasing pawl to enter therein, and in the present invention is employed for use in connection with such pawls. In usual manner the spacebands are suspended by means of their lugs S^4 from a pair of rails B^2 on facing inner sides of the channeled box B , and when released they swing forward into and drop through a channel C and thence into the channeled assembler A in common with the matrices X . In the present invention the

upper end of the foremost spaceband is hindered from entering the channel C by reason of its engagement with a shoulder B^3 provided on opposite sides of an adjustable member B^4 rigidly secured by means of a bracket B^5 to the box B . The space between the shoulders B^3 and the ends of the rails B^2 is sufficient to permit the spaceband lugs S^4 to pass therethrough when the spacebands swing forward and their lower ends enter the channel C ; but when held in angular relation to the channel C the lugs S^4 bridge the offset distance between the shoulders B^3 and rails B^2 . When the escapement parts are at rest a forward pawl D serves to hold the spacebands in their angular position, and as this forward pawl D is retracted to release a foremost spaceband, a rear pawl E enters between the first and second spacebands, clearing in the groove S^2 . The two pawls are interconnected for reciprocating movement in opposite directions, and the weight of the operating connections leading from the operating key K serves to retract the rear pawl and place the forward pawl in position to be engaged by each successive foremost spaceband following the release of a preceding spaceband. Structurally, the escapement is so designed as to conform to the established measurement between the lower ends of the spacebands and the elevator A when in its elevated position. The rear pawl E is a projection from a pawl-operating lever G pivoted on a shaft G^1 supported in opposite walls of the box B ; the lever H from which the forward pawl D projects is centrally pivoted on a shaft H^1 likewise supported in the walls of the box B . This centrally pivoted lever is hinge-connected with the operating lever G by means of a hinge-pin H^2 . This construction is such that when the operating lever G is actuated the two pawls will reciprocate in opposite directions. The pawl end D of the lever H clears through an opening G^2 in the lever G . The operating lever G is offset as at G^3 to clear the front wall of the box B , and returns to a position in alignment with the pawls in order to have a balanced action when actuated. It is connected by means of a link I to the rear end of a centrally-pivoted key lever J . The upper end of the link I is provided with a return bend occupied by an end-angle G^4 of the lever G , a hinge-pin I^1 serving to connect this angle with the return bend of the link I . As thus connected

it will be apparent that when the key K is depressed, reciprocating movement will be imparted to the escapement pawls and a spaceband will be released to and through 5 the channel leading to the assembler.

Having thus described the construction and operation of my invention, what I claim as new and desire to secure by Letters Patent, is:

10. 1. In a typographical assembling machine, combination with spacebands each having a recess in the lower end thereof and a storage box for said spacebands, a pair of reciprocating pawls to co-operate with the recess in said spacebands for the purpose of controlling the release of said spacebands from said storage box.
2. In a typographical assembling machine, combination with spacebands, a storage box 20 therefor, and a pair of reciprocating pawls for controlling the release of said space-

bands from said storage box, means whereby one of said pawls is caused to enter between the first and second spacebands in said box while the other pawl of said pair moves from in front of said spacebands, for 25 the purpose specified.

3. In a typographical assembling machine, combination, spacebands, a storage box therefor, a reciprocating first pawl movable from 30 and to a position in front of each successive first spaceband in said box for permitting the escape thereof, and a reciprocating second pawl movable to a position in front of each successive second spaceband in 35 said box preliminary to the escape of said first spaceband, whereby only one at a time of said spacebands may be permitted to escape from said storage box.

Signed at Pasadena, Los Angeles County, 40 California, this 19th day of October, 1926.

GEORGE E. MARLATT.
